UNITED STATES PATENT OFFICE.

ARTHUR PRIMROSE YOUNG, OF KENILWORTH, AND JOHN HENRY BUTCHER, OF RUGBY, ENGLAND, ASSIGNEES TO GENERAL ELECTRIC COMPANY, A CORPORATION OF NEW YORK.

SOUND-EMITTING DEVICE.

Application filed April 18, 1924, Serial No. 707,502, and in Great Britain April 28, 1923.

Our present invention relates to sound transmitting or emitting instruments and particularly to an improved arrangement of the sound passages or horns of such an instrument whereby a compact design of good appearance is obtained. It is especially applicable to telephone receivers or loud speakers for wireless telephony.

According to the present invention, a compact design is obtained by arranging the sound passage or passages between the sound emitting instrument and a plain or corrugated dome-shaped surface, with or without flared or turned-back edges.

The outer surface of the sound passage may itself form a dome-shaped cover, and one or more helical or radial webs, formed preferably of wood, papier mâché, or sheet metal, may be arranged between the inner and outer surfaces. Obviously the sound passage may consist of a single annular sound horn arranged partly around the instrument, or, alternately, a number of suitably curved sound horns, projecting star fashion from the instrument, may be used.

Various methods of carrying out the present invention are illustrated by way of example in the accompanying drawings: Fig. 1 represents a loud speaking telephone having an annular sound passage provided with a helical web, the outer cover being shown in section; Fig. 2 is an arrangement for intensifying the sound from an ordinary receiver; Fig. 3 is a modification showing a half plan view of a loud speaking telephone with an annular sound horn and Fig. 3^a a part sectional elevation thereof; Fig. 4 is a half plan view of another modification and Fig. 4^a a sectional elevation thereof on the line 4^a of Fig. 4. Like reference numerals are used throughout to denote similar parts.

Referring now to Fig. 1, a loud speaking instrument 11 is provided at its upper end with a projecting opening 12 through which sound generated within the instrument passes. The sound passages are constituted by a dome-shaped cover 13 and a bullet shaped member 14 provided with a reentrant portion 15 adapted to fit over the opening 12. The member 14 is arranged to envelope the instrument 11, as shown, and is supported

from the cover 13 by means of a spider 16. Between the cover 13 and the member 14 may be arranged one or more helical webs similar to 17 and formed of papier mâché, wood, or sheet metal. The path of the sound emitted by the instrument 12 is represented by the arrows, and the sound finally escapes through the openings 20.

Referring now to Fig. 2, a dome-shaped plate 13 is supported upon brackets 18 which also carry a telephone receiver 19 of the ordinary watch case type. Arranged centrally of these supporting brackets is a horn 21 through which the sound produced within the telephone receiver passes, being reflected back from the interior of the cover plate 13.

The constructions shown in Figs. 3 and 4 are substantially similar to that of Fig. 1 but are especially suitable for mounting on a wall or on a vertical partition of a wireless cabinet. Instead of the helical web 17, vertical webs 22 are provided between the surfaces 13 and 23 of the sound passage and these webs may serve to support the inner member and the receiver. In Fig. 3 the instrument 11 is substantially enclosed by the surface 23 and a mirror 24 supported by the edge thereof. The dome-shaped surface 13 in Figs. 4 and 4^a is provided with a curled round edge 25 and the other surface 23 is correspondingly shaped so that the sound passages are substantially clear of the instrument. Any of the constructions above described may be supported with the dome-shaped casing or cover plate 13 above or below the instrument 11; or the apparatus may be hung from a nail or the like, or supported by other means, so that the axis of the dome-shaped surface is horizontal.

A loud speaking telephone constructed upon these principles may be used as a table instrument; or on account of its compact design, it is very suitable for mounting in a compartment of a cabinet type of wireless receiving set.

It will be observed that by means of the constructions illustrated it is possible to form a sound passage of any configuration desired and of a length greater than the height of the dome-shaped member. In this way a sound passage of the desired length may be obtained

and the instrument may be made more compact than when a horn of the usual type is employed.

What we claim as new and desire to secure 5 by Letters Patent of the United States, is,—

1. A sound emitting instrument comprising a dome-shaped member, a sound producing instrument located within said member and means surrounding said instrument and 10 forming the inner wall of a sound passage, the outer wall of which is formed by the dome-shaped member.

2. A sound emitting instrument comprising a dome-shaped member, a sound producing instrument located within said member and means surrounding said instrument and forming the inner wall of an annular sound 15 passage, the outer wall of which is formed

by the dome-shaped member, said passage being subdivided into a plurality of separate 20 passages by a plurality of radial ribs.

3. A sound emitting instrument comprising a dome-shaped member, a sound producing instrument located within said member and means surrounding said instrument and 25 forming the inner wall of an annular sound passage, the outer wall of which is formed by the dome-shaped member, said passage being subdivided into a plurality of separate passages by a plurality of radial ribs, said means 30 being supported on said radial ribs.

In witness whereof, we have hereunto set our hands this thirty first day of March, 1924.

ARTHUR PRIMROSE YOUNG.
JOHN HENRY BUTCHER.
